UNITED STATES PATENT OFFICE

2,477,716

SCALE AND SEDIMENT ELIMINATOR

Urban B. Best, St. John, and Virgil L. Hudson,
Great Bend, Kans.; Ida Louise Hudson, executrix of said Virgil L. Hudson, deceased, assignor of Virgil L. Hudson's interest to Ida Louise Hudson

Application January 16, 1947, Serial No. 722,384

5 Claims. (Cl. 210—43)

1

This invention relates to new and useful improvements in cleaners and more particularly to a device adapted to catch and hold scale, rust, dirt and all foreign matter that might accumulate or be found in the water or liquid in the cooling system of any water, or other liquid cooled internal combustion engine or motor.

The primary feature of this invention is to provide a device of the character referred to having a pair of removable filtering elements at each end thereof which are adapted to specifically catch and hold all scale, rust, dirt and all foreign sediment or matter in liquids circulating through a cooling system.

Another important feature of this invention is to provide a device of this character having said filtering elements adapted for easy and quick removal therefrom for replacing with new elements.

A further feature of this invention is to provide a device of the character referred to that is efficient and reliable in operation, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a perspective view of the device constructed in accordance with the present invention.

Figure 2 is a vertical longitudinal sectional view taken through the center thereof.

Figure 3 is a sectional view taken on line 3—3 of Figure 2.

Figure 4 is a sectional view taken on line 4—4 of Figure 2.

Figure 5 is a sectional view taken on line 5—5 of Figure 2, and

Figure 6 is a sectional view taken on line 6—6 of Figure 2.

Referring now to the drawings in detail, wherein for the purpose of illustration, we have disclosed a preferred embodiment of the invention, the numeral 5 represents an outer filter casing of rectangular shape having its end edges bent outwardly to form flanges 6.

Frictionally held within each end of outer casing 5 are a pair of inner casings 7 and 8.

The inner opposing ends 9 and 10 of said inner casings 7 and 8 are provided with perforations 11 and 12 toward one side of said ends.

2

Connecting the inner ends 9 and 10 of said inner receptacles 7 and 8 is a baffle plate 13 which is spaced slightly above an inlet nipple 14 in the bottom of the outer casing at its center.

5 The lower portions of casings 7 and 8 are provided with inlet chambers 15 and 16 having preferably arched openings 17 at the inner ends of said chambers.

The inner casings are similar in construction and a description of one will suffice for the other.

10 A longitudinal baffle plate 18 is suitably secured at one edge 19 to the inner end of the inner casing at its imperforate side and inclines toward the perforate side and the outer edge 20 of said baffle plate 18 is spaced slightly inwardly from the outer end of the outer casing. An opening 21 is provided in the upper wall 22 of inlet chamber 15 on the side of baffle plate 18 adjacent the imperforate side of the inner cas-

15 ing.

An outlet nipple 22a is provided in the outer casing 5 slightly above baffle plate 13.

20 A pair of end plates 23 and 24 having centrally located sockets 25 and ribs 26 radiating from said sockets to the corners of said plates is held against the ends of the outer casing 5 by a pair of clamps 27 and 28 having adjustable set screws 29 at the center thereof which fit into sockets 25, said clamps 27 and 28 having clamping arms 30 radiating from the centers of said clamps which are adapted to clamp said plates 23 and 24 to the flanges 6 of the outer casing as shown in Figure 1 of the drawings.

25 In operation, water, or other liquid used in the cooling system enters inlet nipple 14, under pressure from the water pump, or by gravity, and strikes upwardly against baffle plate 13 and is diverted equally through arched openings 17 into chambers 15 and 16 respectively.

30 The water in chambers 15 and 16 is then forced upwardly through openings 21 in the upper walls 22 of said chambers and passes through filtering material 31 loosely packed at the imperforate side of baffle 18 collecting sedimentation at the side of the baffle provided with the filtering material, the water then passing around the end 20 of said baffle 18 into the perforate portion of the chamber and through perforations 11 and 12 and then discharged outwardly through outlet nipple 22a.

35 The inner casings are easily and quickly slipped out of said outer casing for replacing when desired.

40 In view of the foregoing description taken in conjunction with the accompanying drawings it is believed that a clear understanding of the con-

struction, operation and advantages of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

We claim:

1. A sediment trap comprising an outer casing having an inlet in its bottom and an outlet in its top, a pair of inner casings carried in the end portions of said outer casing, a baffle extending between the inner ends of said inner casings and separating the inlet from the outlet, an inlet chamber in the lower portion of each of said inner casings having openings adapted to receive liquid entering the inlet and impinging against the baffle, the upper portions of said inner casings providing sediment collecting chambers having openings leading from the inlet chambers, and filtering material in said collecting chambers, the inner ends of said inner casings at the sediment collecting chambers having an opening through which the filtered liquid passes to the outlet.

2. A sediment trap comprising an outer casing having an inlet in its bottom and an outlet in its top, a pair of inner casings carried in the end portions of said outer casing, a baffle extending between the inner ends of said inner casings and separating the inlet from the outlet, an inlet chamber in the lower portion of each of said inner casings having openings adapted to receive liquid entering the inlet and impinging against the baffle, said inlet chambers having an opening in its upper wall for passage of liquid to the upper portions of said inner casings, longitudinally inclined baffles in the upper portions of said inner casings, and filtering material in the upper portion of said inner casings, at one side of said longitudinally inclined baffles, the inner ends of said inner casings provided with an opening at the other side of said longitudinal baffles through which the filtered liquid passes to the outlet.

3. A sediment trap comprising an outer casing having an inlet in its bottom and an outlet in its top, a pair of inner casings carried in the end portions of said outer casing, a baffle extending between the inner ends of said inner casings and separating the inlet from the outlet, an inlet chamber in the lower portion of each of said inner casings having openings adapted to receive liquid entering the inlet and impinging against the baffle, said inlet chambers having an opening in its upper wall for passage of liquid to the upper portions of said inner casings, baffle plates extending longitudinally in the upper portions of said inner casings, and filtering material in the upper portion of said inner casings, at one side of said longitudinally extending baffles, the inner ends of said inner casings provided with an opening at the other side of said longitudinal baffles through which the filtered liquid passes to the outlet, and end plates removably secured at the ends of the outer casing.

4. In a device of the class described, a horizon-

tally disposed outer casing having its ends open, an inlet extending through one wall of said casing, an outlet arranged in the opposite wall of said casing, a pair of inner casings carried by the end portions of said outer casing, horizontal partitions in the inner casings to provide inlet chambers in the lower portion of said inner casings, a baffle plate extending longitudinally in the upper portions of said inner casings dividing same into a sedimentation chamber and an outlet chamber, said partitions having openings therethrough leading to said sedimentation chambers, filtering material within said sedimentation chambers, a baffle plate carried by the inner ends of said inner casings and between the outlet and inlet, said last named baffle adapted to divert water into the inlet chambers, the outlet chambers at the inner ends of said inner casings having perforations through which the liquid passes from the outlet chambers to the outlet, and end plates closing the outer ends of said outer casing.

5. In a device of the class described, a horizontally disposed substantially rectangular outer casing having its ends open, an inlet extending substantially through the center of the lower walls of said casing, an outlet arranged in the upper wall of said casing, a pair of substantially rectangular inner casings carried by the end portions of said outer casing, said inner casings being open at their inner ends and closed at their outer ends, a horizontally disposed partition carried by each of said inner casings to provide inlet chambers in the lower portions of said inner casings, a vertically disposed baffle carried by the upper portion of each of said inner casings adapted to divide said upper portions into a sedimentation collecting chamber and outlet chamber, said partitions having openings between said sedimentation chamber and inlet chamber, filtering material in said sediment collecting chamber, a baffle plate carried between the inner ends of said inner casings and directly between said inlet and outlet, said last named baffle adapted to divert liquid striking same into the inner ends of said inlet chambers, the inner ends of said inner casings at the outlet chambers provided with perforations through which liquid passes to the outlet, a pair of end plates closing the outer ends of said outer casings, and a pair of clamps adapted to bear against said plates, said outer casing having flanges at its ends and said clamps provided with L-shaped arms which grip the flanges to removably secure the end plates in position.
